PUMP PRIMER

James M. Cox, Fall River, Mass.

Application September 28, 1945, Serial No. 619,047

3 Claims. (Cl. 103—113)

1

The device of the present invention comprises an improvement in pump primers and is adapted for use on reciprocating, centrifugal or rotary pumps either high or low lift.

Experience with water pumps, as usually employed in town and city water works and like public utilities, has taught that the safety factor of necessity transcends the utilitarian aspect. Consequently water ejectors, because of their dependability, are presently extensively used in water works. Experiments have proven that a primer made, and installed on a pump, in accordance with the teaching of the present invention, may be used with any type of vacuum creating equipment.

Objects of the invention are the provision of a transparent shatter-proof non-frangible body which is mounted directly on the pump and through which the "prime" or absence thereof is discernible from any position around the pump; to equip the primer with a thermometer in constant engagement with the water being pumped thereby making the water temperature available to anyone in proximity to the pump; to include in the primer assembly a float controlled mercury switch to automatically shut off the vacuum pump when the water pump is fully primed and free of air; to provide an auxiliary shut off in the primer which may consist of a ball check which automatically functions to prevent passage of water into the pump when the priming cycle has been consummated; to provide a relatively small and compact primer, detachably engageable with the pump, which at all times makes available, at a glance, the internal condition of the primer body including the temperature, fluidity, color, turbidity, etc. of the prime; and to provide an automatic sight flow primer which after actual use on centrifugal pumps has been found to increase the safety factor.

Other objects will be apparent from the following description of the present preferred form of the invention wherein:

Figure 1 is a perspective view of a primer constructed in accordance with the present invention;

Figure 2 is an elevational view of the same, a part thereof being broken away to disclose details, the latter being shown connected to a schematically illustrated vacuum pump;

Figure 3 is a side elevational view of the primer illustrating its application to a portion of a centrifugal pump; and

Figure 4 is a detail fragmentary sectional view of the invention illustrating to advantage the

float operated switch mounted on top of the primer body.

In order to illustrate the application of the invention, I have in Figure 3 shown a part of a centrifugal pump 5 of standard construction which is equipped with a primer made in accordance with the teaching of my invention, the primer being generally designated 6. Additionally to illustrate the application of this invention, I have in Figure 2 shown a portion of an auxiliary or vacuum pump 7 and a motor for operating the same 8.

The primer of this invention includes a transparent shatter-proof non-frangible body 9 preferably of cylindrical configuration and equipped with a suitable pipe or conduit 10 which engages the primer with the pump 5 and which also places the primer in communication with the pump. The body 9 may be of a plastic material such as cellulose acetate or methyl methacrylate ("Plexiglas"). The opposite ends of the body 9 are embraced by discal plates 11. Each of the plates issues into a polygonal block 12 upon each of which a jam nut 13 is mounted. The plates 11 are held in contiguous relation to the body 9 by rods or braces 14 the ends of the latter being screw threaded and extended completely through the plates 11 for the reception of retaining nuts 15. The jam nut 13 on the bottom plate engages the pump connecting pipe 10 while the top jam nut 13 engages one end of a pipe 16 which latter communicates with the vacuum pump 7.

The upper of the plates 11 also carries a switch arm 17 which is movably mounted under influence of a float 18 to close an electrical circuit through a mercury switch 19, thereby applying current from source 31 to motor 8. The float 18 is pendently carried by one end of a shaft 20, the upper end of which latter extends through an opening in the top plate 11 and is engaged with the switch arm 17 through the medium of a pin 21 loosely mounted in an elongated slot 22 formed in the switch arm 17 as advantageously illustrated in Figure 4. The shaft 20 operates through a gland nut mounted in the upper plate 11 in a liquid tight manner. Consequently, raising and lowering of the float 18 is effected without loss of liquid from the primer body 9.

The upper of the plates 11 likewise carries a gage also of standard design and for use in an obvious manner.

The bottom plate 11 is provided with a central aperture 24 through which the prime passes into the pump 5. The bottom plate is additionally

provided with a drip opening 25 for flow of liquid which is controlled by a valve outlet 26.

The float 18 is raised in the body 9 under influence of the liquid or prime.

As an additional safety feature, to supplement the float 18, I employ a check valve which is automatically operated by the rise of the fluid in the primer and may consist of a float preferably made of plastic 27 which is adapted to cover over the outlet opening to the vacuum pump with which the pipe 16 communicates, as shown in Figure 2.

With the device of the present invention placed directly on the pump, the prime is visible at all times, the temperature of the water is visible at all times by reason of the use of thermometer 30, and the condition of the water is also discernible through the wall of the primer body. It is, of course, well known in the art to employ an auxiliary vacuum pump and priming tank where the prime is visible on the tank through gage glasses. However, experience has proven that with the valves closed on the main pump, water shows in the priming tank but the main pump will be devoid of water. This is not possible with the present invention. Furthermore, by making the body of a non-shatterable and a non-frangible material, there is no possibility of glass splinters dropping into the close fitting internal parts of the pump.

If desired, the pump primer outlet pipe 10 may be equipped with a strainer 28 to intercept extraneous materials from passing into the pump 5.

Although I have herein described the preferred form of the invention, I am nevertheless aware that various changes may be made within the scope of the claims hereto appended.

What I claim is:

1. A pump primer comprising a pump, a primer mounted on and in operative communication with the pump, including a transparent shatter-proof body, with fluid inlet and outlet openings, a float engaged with the body and movable to cut off passage of fluid from the body when the fluid in the body reaches a predetermined level, and a free float independent of the first said float and operable to seat against the outlet opening to prevent passage of fluid from the body, in the event of failure of said first float.

2. In combination with a centrifugal pump and a vacuum pump, a primer mounted on the pump, and in communication with both the centrifugal and the vacuum pumps, the primer comprising a transparent shatter-proof, non-frangible body adapted for the reception of the prime liquid, and a pair of independent floats arranged within the body, means constraining one of said floats to move in a predetermined path in response to variations of the level of fluid within the body and operable to cut off passage of fluid from the body when said fluid reaches a predetermined level, and the other of said floats being freely movable and operable to cut off passage of fluid from the body in the event of failure of the first float.

3. In combination with a centrifugal pump and a vacuum pump, a primer mounted on the pump and in communication with both the centrifugal and the vacuum pumps, the primer comprising a transparent, shatter-proof, non-frangible body adapted for the reception of the prime liquid, a float in said body, a switch on the body in operative communication with the vacuum pump, means connecting the float to the switch to shut off the vacuum pump when the prime liquid reaches a predetermined level in said body, and a free float independent of the first said float and operable to prevent passage of fluid from the body, in the event of failure of said first float.

30 JAMES M. COX.
